CLAIM

The ornamental design for a sorted drill bit case, as shown and described.

DESCRIPTION

FIG. 1 is a top, front, and left side perspective view of a sorted drill bit case showing our new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a bottom plan view thereof; and,

FIG. 7 is a rear elevational thereof.

The broken-line disclosure in the views is understood to be for illustrative purposes only and forms no part of the claimed design.
